UNITED STATES PATENT OFFICE

ROY R. BIRCHFIELD, OF HOLLY RIDGE, LOUISIANA, ASSIGNOR OF ONE-HALF TO I. F. CRYER, OF BOSSIER PARISH, LOUISIANA

RAIL-SANDING DEVICE AND CLEANER THEREFOR

Application filed July 6, 1929. Serial No. 376,348.

The object of this invention is to provide improved means for sanding rails of railroad tracks, and means for keeping the sand pipes free from obstruction, due to the packing of 5 the sand or to the other causes.

A further object is to provide air controlled agitating means, for the purpose indicated.

A further object is to provide a cylinder 10 and a piston therefor, and means controlled by the piston for rotating a plurality of agitators, one of which may be located in the duct leading from the sand dome, the others being positioned in the pipes thru which the 15 sand is distributed.

With the foregoing and other objects in view, the invention consists in the novel construction and arrangement of elements disclosed, it being understood that modifications 20 may be made within the scope of the claims without departing from the spirit of the invention.

In the drawings forming part of this application:—

25 Figure 1 is a view of the device in top plan.

Figure 2 is a view in vertical section, on line 2—2 of Figure 1.

Figure 3 is a view in vertical section on line 30 3—3 of Figure 2.

Figure 4 is a view in end elevation.

A main casting or body is designated 10 and is provided with a chamber in which cylinder 11 is mounted, the casting also being 35 provided with chambers or cut away portions 12 and 13 facilitating the mounting of certain elements described below. These chambers 12 and 13 may be closed by cover plates such as 14 and 15.

40 Within the cylinder 11, I mount a piston 16 provided with packing as shown for instance at 17, the piston having reduced annular portions at 18 and 19 permitting of the passage of sand when in registration with the sand ports, shown at 18'—18''—19' and 19''. These ports just referred to are in communication with the sand pipes.

45 A pipe or element 20 is adapted for connection with the said dome, and connections 21 and 22 threaded into the lower part of the

main casting are adapted for connection by means of unions such as 23 with pipes 24 and 25.

In each of the pipes last named thru which sand is applied directly to the rails, I provide 55 agitating devices which in the present instance are shown as including chains 26, the latter being connected respectively with shafts or stems 27 and 28, and these elements last named carrying pinions such as 29 adapt- 60 ed for rotation by means of a rack bar.

The pinions are rigid with reference to stems 27 and 28, and the rack bar is slidable within cut away portions in the body shown for instance at 30, the rack being designated 65 31 and the two rack bars shown constituting upper and lower elements of a reciprocable frame which is movable transversely thru the body or casting 10, in view of the operating means described below. 70

The piston 16 has connected with opposite ends thereof stems or rods such as the elements 40 and 41, and surrounding the latter are springs 42 and 43, the outer ends of the springs being held at 44, and adjusting nuts 75 for the stems being provided at 45.

Each end of the cylinder is provided with a head such as that shown at 46, these elements being threaded on to the ends of the cylinder, and the rods 40 and 41 extend thru 80 the heads and thru the cuffs or elements 46 against which the springs 42 and 43 abut at their inner ends.

Relief valves are shown at 47 and 48, and air under pressure is introduced thru pipes 85 49 and 50, so that the piston 16 may be moved in either direction, according to the operation of valves not shown, admitting air for the purpose specified.

In the position of Figure 2 the reduced 90 portion 19 of the plunger, providing a port or passageway, is in registration with ports 19' and 19'', and sand passes thru pipe 25 to the rail of the track.

An agitating device 53 is carried by stem 95 53', and the latter supports rigidly thereon a pinion 54 adapted for engagement with upper rack 31. Ducts 55 and 56 passing thru the body 10 connect respectively with the cylinder 11 and the ports 18'' and 19.'' 100

What is claimed is:—

1. In a device of the class described, a body portion, a cylinder mounted therein, a piston within the cylinder, said cylinder being provided with ports controlled by the piston, ducts in communication with the ports, agitating devices within said ducts, and means connected with opposite ends of the piston, and movable through the body and alongside of the cylinder, for rotating the agitating devices upon the operation of the piston.
- 5 2. In a device of the class described, a body portion, a cylinder mounted therein and provided with ports, a piston controlling the ports of the cylinder, ducts communicating with said ports, agitating devices within the ducts, a reciprocable rack, means rigid with the agitating devices and controlled by the rack, means for admitting air under pressure 10 to opposite ends of the cylinder, and means connecting the rack with opposite ends of the piston.
- 15 20

In testimony whereof I affix my signature.
ROY R. BIRCHFIELD.
